UNITED STATES PATENT OFFICE.

SAMUEL SEROTA, OF NEW YORK, N. Y.

SAFETY RAZOR.

Application filed December 2, 1922. Serial No. 604,537.

This invention relates to safety razors.

One object thereof is to provide a device of the character described having means whereby both the cutting edges of the safety 5 razor blade may be sharpened on a strop with the various parts of the device remaining in the position assumed by them when the safety razor is used in shaving, so that the razor blade may be readily stropped 10 without necessitating the readjustment or removal of parts, merely by positioning the strop in operative relation to the blade.

Another object is to provide a device of the character described having simple means 15 for reversibly holding the safety razor blade so that the latter may be easily reversed so as to present first one and then the other cutting edge, and which means shall also permit the blade to be readily secured in position on the blade holder and removed 20 therefrom as desired.

Other objects of this invention will in part be obvious and in part hereinafter pointed out.

25 Certain features herein shown and described are shown, described and claimed in my co-pending application Serial No. 595,688 filed in the United States Patent Office on the 19th day of October, 1922, and accordingly not claimed herein.

With the above exception the invention accordingly consists in the features of construction, combinations of elements and arrangement of parts which will be exemplified in the construction hereinafter described and of which the scope of application will be indicated in the following claim.

In the accompanying drawing, in which is shown one of various possible illustrative 40 embodiments of this invention,

Fig. 1 is an end elevational view of a safety razor embodying my invention, with a razor strop positioned thereon shown in dotted lines, the razor handle being broken 45 away to conserve space;

Fig. 2 is a plan view corresponding to Fig. 1;

Fig. 3 is a sectional view cut along line 3-3 of Fig. 1;

50 Fig. 4 is a sectional view through the blade holder bar cut along line 4-4 of Fig. 2; and

Fig. 5 is a plan view of the razor blade preferably employed with my invention.

55 Referring in detail to the drawing, 10 indicates a handle member secured to a frame

11 on which the various parts of the safety razor are mounted. The frame 11 is provided at the front and rear ends thereof with upstanding bearing members 12, 12' in 60 which are journaled a pair of rollers 13, 13' in vertical alignment and spaced from each other. At one end of the upper roller 13 is mounted a gear 14 adapted to mesh with the gear 15 at the corresponding end 65 of the roller 13'. A pair of guide rollers 16, 16' are journaled to either side of and below the roller 13' for the razor strop 17 which when the blade is to be sharpened passes over these rollers 16, 16' and beneath the 70 roller 13' as shown in Fig. 1.

Extending from the upper ends of the frame 12 is a pair of end pieces or connecting bars 12^a, 12^b, each secured at one end to the corresponding end of the roller 13 so as 75 to be movable therewith and receiving between its free ends the blade holder. The latter comprises a cross bar 18 pivotally held between the connecting block 12^a, 12^b by means of trunnions 18^a, 18^b journaled in the 80 free ends of said connecting blocks. The material of the cross bar is punched out adjacent the ends thereof to provide raised tongues 18^c adapted to engage in corresponding elongated slots 19^c in the safety razor 85 blade 19. A central opening 19^d is further provided in the blade 19 to receive a central raised portion 18^d formed in the cross bar 18. In inserting the razor blade in the holder, one of the tongues 18^c is disposed in engaging 90 position over the corresponding opening 19 and the safety razor blade slid thereunder until the other prong engages in the other opening. The central raised portion 18^d then registers in the opening 19^d in the blade and 95 acts as a stop to prevent movement of the blade relative to the cross bar. Adjacent the trunnion 18^a is a rectangular hub 18^e adapted to rest in a rectangular slot 18^f formed in the corresponding connecting 100 block 12^a. The opposite block 12^b is provided with a spring 20 which acts against the trunnion 18^b so as to normally keep the rectangular hub 18^e of the opposite trunnion 18^a in the rectangular slot 18^f. When 105 it is desired to reverse the blade the cross bar 18 is pushed forward so that the trunnion 18^b will act against the spring 20 and the hub 18^e in this way moved out of the rectangular slot 18^f. The trunnion 18^a will 110 then be loose in said slot, thus permitting the rotation of the cross bar.

A guard 21 is provided for the razor blade comprising a horizontal supporting member 21^a slidable in the guide 22 secured at the top of the handle 10. Extending from the 5 support 21^a is a thumb piece 21^b for manipulating the guard. A pin 23 extends from the member 21^a into the handle in co-operative relation to a spring member 24 secured therein. The guard portion is 10 shown at 25 and has at either end thereof upturned engaging lips 25^a, 25^b adapted to receive the ends of the blade 19. As will be readily understood, the spring 24 acts against the pin 23 so as to normally urge 15 the lips 25^a, 25^b against the razor blade. When it is desired to free the razor blade, the thumb piece 21^b is pushed inward against the action of the spring 23, thus moving the guard away from the blade until 20 the lips 25^a, 25^b are out of engagement therewith.

In stropping the blade, the strop 17 is passed over the guide roller 16 underneath the gear wheel 13' over the other roller 16', 25 and underneath the razor blade and above the guard member. As the handle 10 is moved back and forth, the blade holder including the connecting blocks 12^a, 12^b, the cross bar 18, and the blade thereon is given 30 a rocking movement by the operation of the gears 18, 18', thus presenting first one and then the other side of one razor edge. The other razor edge is then sharpened by

reversing the cross bar 18 in the manner already described.

It will thus be seen that there is provided a device in which the several objects of this invention are achieved and which is well adapted to meet the conditions of practical use.

As various possible embodiments might be made of the above invention and as various changes might be made in the embodiment above set forth, it is to be understood that all matter herein set forth or shown in the accompanying drawings is to be interpreted as illustrative and not in a limiting sense.

Having thus described my invention I claim as new and desire to secure by Letters Patent:—

A device of the character described comprising a handle member, a supporting frame secured thereto including connecting bars pivoted to said frame, a double edge razor blade, a holder releasably secured to the blade between the cutting edges thereof, and revolubly mounted on said bars to selectively hold either edge of the blade in effective position, and a spring pressed member disposed in operative relation to said holder.

In testimony whereof I affix my signature.

SAMUEL SEROTA.
